UNITED STATES PATENT OFFICE.

HERMON L. VAN VALKENBURG, OF MILWAUKEE, WISCONSIN, ASSIGNOR TO
INDUSTRIAL CONTROLLER COMPANY, OF MILWAUKEE, WISCONSIN, A COR-
PORATION OF WISCONSIN.

MAGNETIC CONTACTOR.

1,341,867.

Specification of Letters Patent. Patented June 1, 1920.

Application filed July 25, 1918. Serial No. 246,636.

To all whom it may concern:

Be it known that I, HERMON L. VAN VALKENBURG, a citizen of the United States, residing at Milwaukee, in the county of Milwaukee and State of Wisconsin, have invented a certain new and useful Improvement 5 in Magnetic Contactors, of which the following is a specification.

My invention relates to electromagnetic contactors, more particularly for use on alternating current. One of the principal objects of the invention is to provide a contactor which will not "chatter", even though it may have some inaccuracies due 10 to manufacture in quantity. The tendency to chatter is greatly reduced by providing a comparatively large surface over which the armature of the electromagnet may contact the pole piece, and so designing the apparatus that said parts will engage over the 15 entire available contact area. It is my purpose to provide means whereby contact may always occur over the entire surface even though the device may be manufactured in 20 quantity and hence not be formed with that extreme care and nicety which has heretofore been necessary to reduce the vibration 25 in this class of apparatus. With this in view, I make the connection between the 30 armature lever and the shaft somewhat loose and hence the armature is slightly independent of the shaft and may adjust itself to the stationary magnet pole. Another object of the invention is to provide a construction by which the parts may be brought 35 closely together without weakening them, thus making the device more compact and reducing the amount of space and material required for it. In carrying out this feature 40 of the invention I have made it possible to reduce the length of the main shaft. Moreover, by reducing the length of the shaft its relative rigidity and stiffness is increased. Still another object is to provide 45 a construction lending itself to the easy removal of the magnet coil for replacement and repairs.

I accomplish my objects by mechanism illustrated in the accompanying drawings 50 in which—

Figure 1 is a front view of the complete apparatus.

Fig. 2 is a sectional elevation on the line 2—2, Fig. 1.

Fig. 3 is a sectional elevation on the line 55 3—3, Fig. 1.

Fig. 4 is a sectional elevation on the line 4—4, Fig. 2.

Fig. 5 is a perspective view of the armature pole piece and associated parts. 60

Similar numerals refer to similar parts throughout the several views.

Ordinarily the apparatus is mounted upon a panel 1 of marble, slate or other material. In the design selected to illustrate the invention the main shaft 2 is journaled in brackets 3, 3 suitably fastened to the front of the panel. Except at the reduced cylindrical ends 6 where the shaft is journaled in the brackets, it is square and carries the 70 switch arms 8 which are here shown to be three in number. As the switches themselves are not particularly concerned with the invention it will be sufficient to say that in the form shown the shaft is inclosed in 75 an insulating sleeve 9 and the switch arms are held to it by clips 10. A spring contact terminal 12 is carried at the free end of each switch arm in position to engage a co-operating stationary contact terminal 13, fastened 80 in any suitable manner to the panel.

Now referring more particularly to the electromagnetic parts of this device, a pole piece 20 is rigidly fastened to the panel and encircled by a coil 21 by which it is magnetized. This coil is self contained in the sense that it can be removed as a whole by slipping it forward off the end of its core or pole piece. In the form illustrated the pole piece forms part of a U-shaped frame which, 85 when the armature is in closed position, forms with it a closed magnetic circuit. By preference the pole piece and frame are laminated. The armature consists of a plate 90 arranged in the plane of the magnet 95 frame and having on each side of it a number of laminations 26. These are preferably held in place by suitable outer plates 27. Thus the armature is built up of a center plate having a preferably equal number 100 of laminations on each side of it. The armature is built up to a considerable width, as is also the pole piece, thus giving a relatively large area over which the two

may contact each other. In the devices heretofore made, it is frequently found that the armature does not seat squarely against the pole piece. I have avoided the difficulty by employing a comparatively thin plate 25 and forming a square hole 30 in it slightly larger than the shaft. The result is that the armature rotates the shaft far enough to obtain good contact when the 10 arms are closed and yet there is sufficient lost motion to enable the armature to seat squarely upon the pole piece. The thinness of the plate 25 permits the parts to be appreciably out of alignment without throwing 15 the armature out of alignment with the pole piece. In other words there is some room to come and go angularly, that is, in a plane perpendicular to the shaft and also laterally in both directions. If the armature had a long bearing on the shaft, a comparatively small mis-location of the shaft might readily permit the armature to contact the pole piece only at one corner or along one edge or side, whereas with my 20 construction where the length of bearing along the shaft is greatly reduced there is room for automatic adjustment of the armature in every direction without however, defeating its function of closing and opening 25 the switch.

An arm 36 which is preferably integral with plate 25 extends back under the magnet frame to serve as a stop for preventing the armature from swinging forward when the 30 pole piece is deenergized. The arm and plate are positioned laterally upon the shaft by means of clips or keepers 33 located a slight distance away from the plate on either side of it. These clips are fastened 35 in place by screws 35 or other appropriate means. One of the advantages in having the arm thin is that it facilitates the removal of the coil 21 from the pole piece. Being thin, the plate can be shifted laterally on the shaft a greater distance before 40 striking the sleeve 9 than if the plate were as thick as the armature. In my device, by reason of the thinness of the plate, it and its armature can be moved sidewise far enough 45 to permit the coil to be drawn off of the pole piece without striking the armature.

The operation of the device will be apparent. When the pole piece becomes energized and attracts the armature the latter will rotate the shaft and move the switch arms to open or closed position as the case may be, the present case showing the switch arms closing when the armature moves up to the pole piece. The novel mechanical connection between the armature and the shaft permits the armature to adjust itself and seat accurately upon the pole piece even though the parts may be appreciably out of position or the parts may exhibit noticeable 55 inaccuracies of manufacture.

Having thus described my invention, what I claim as new and desire to secure by Letters Patent, is:—

1. An alternating current magnetic contactor having a main operating shaft one portion of which is polygonal in cross section, a pole piece, and an armature fitting somewhat loosely over the polygonal portion of said shaft whereby the armature is capable of operating the shaft but is, within reasonable limits, independent of said shaft, thus enabling it to adjust itself to the pole piece.

2. An alternating current magnetic contactor having a main operating shaft, one portion of which is polygonal in cross section, a pole piece, and an armature comprising a plate and permeable material secured to said plate to form an armature, the width of the plate being less than the total width of the armature and the plate loosely fitting the polygonal portion of the shaft.

3. An alternating current magnetic contactor, having a main operating shaft, a comparatively thin plate engaging said shaft for rotating it, an electromagnetic pole piece, and an armature co-operating therewith, said armature being mounted upon said plate and being of a width greater than the thickness of the plate.

4. A magnetic contactor having a main operating shaft, a pole piece, a coil for magnetizing it, an armature co-operating with the pole piece, said armature being connected to the shaft for rotating it and being slideable longitudinally of the shaft whereby it may be shifted to one side of the pole piece to permit the removal of the coil.

5. A magnetic contactor having a polygonal operating shaft, a pole piece, a magnet coil surrounding said pole piece, an armature co-operating with the pole piece, said armature fitting over said shaft loosely enough to be slideable longitudinally, whereby it and the armature may be shifted laterally to permit the coil to be withdrawn from the pole piece without the necessity of removing the armature from the shaft.

6. A magnetic contactor having a main operating shaft, a pole piece, a coil for magnetizing it, a relatively thin plate carrying an armature adapted to co-operate with the pole piece for actuating said plate and rotating the shaft, a stationary stop in line with said plate, said plate having an arm extending from it and adapted to engage said stop for limiting the movement of the armature away from the pole piece, said plate being slideable to enable it to be shifted to one side to permit the coil to be withdrawn from the pole piece.

7. An alternating current magnetic contactor having a main operating shaft, an insulating sleeve thereon, switch arms fastened to the shaft over the sleeve, the sleeve

- extending along the shaft beyond the outermost switch arm, an electromagnet located at the side of the switch arms and consisting of a pole piece and a removable coil surrounding it, and an armature coöperating with the pole piece, said armature being of considerable width, lengthwise of the shaft, and being secured to the shaft by means of a plate slideable lengthwise of the shaft, said plate being thin compared to the width of the armature, whereby the armature may be shifted close to the nearest switch arm, for removal of the coil, without interference between the sleeve and the plate.
8. A magnetic contactor having a main operating shaft having a squared portion, a stationary pole piece, an armature, the pole piece and armature having considerable area over which they may make contact, and a lever supporting said armature, said lever being adapted to engage said shaft for rotating it, and said lever being loosely connected to said shaft whereby the armature

may seat squarely against the pole piece regardless of ordinary inaccuracies of alignment of the shaft. 25

9. A magnetic contactor having a main operating shaft, a pole piece, an armature coöperating with the pole piece, a relatively thin plate for connecting the armature with the shaft for rotating it, said plate being slideable lengthwise of the shaft, and a removable clip fastened to the shaft for normally holding the plate in position. 30

10. An alternating current magnetic contactor having switch arms, a shaft carrying said arms for operating them, an electromagnetic pole piece, an armature coöperating therewith, a plate carrying said armature and engaging the shaft for rotating it, 40 said plate being shiftable along the shaft and normally held in position laterally by clips removably attached to the shaft. 35

In witness whereof, I have hereunto subscribed my name.

HERMON L. VAN VALKENBURG.
